UNITED STATES PATENT OFFICE.

WILLIAM E. SPARKS, OF NEW HAVEN, CONNECTICUT, ASSIGNOR TO SARGENT & CO., OF SAME PLACE.

REVERSIBLE LATCH.

SPECIFICATION forming part of Letters Patent No. 314,738, dated March 31, 1885.

Application filed November 17, 1884. (No model.)

To all whom it may concern:

Be it known that I, WILLIAM E. SPARKS, of New Haven, in the county of New Haven and State of Connecticut, have invented a new 5 Improvement in Knob-Latches; and I do hereby declare the following, when taken in connection with accompanying drawings and the letters of reference marked thereon, to be a full, clear, and exact description of the same, 10 and which said drawings constitute part of this specification, and represent, in—

Figure 1, a view of the interior mechanism of the latch, one plate of the case removed to expose such mechanism; Fig. 2, a section 15 through the locking-slide on line *xx*; Fig. 3, a longitudinal section through the hub, showing the transverse slot *r*.

This invention relates to an improvement in that class of knob-latches in which the latch-bolt is made reversible, to be set for a right or 20 left hand door without removing the covering-plate of the case, and is an improvement upon the invention of my own for which Letters Patent No. 306,545 were granted. In my 25 said patent the arrangement is such that the latch-bolt can only be reversed when the lock-bolt is thrown outward; and for the better understanding of my present invention I will briefly describe this construction so far as the 30 two are substantially alike.

A represents the face-plate; *B*, the case within which the mechanism is arranged; *C*, the hub through which the knob-spindle passes, and which is provided with the arms *D E*, 35 one upon one side and the other upon the opposite side of the axis, whereby the knob may be turned in either direction.

F is a slide arranged within the case and guided longitudinally upon a stud, *a*, in the 40 case or otherwise. From this slide two arms extend rearward, the one, *G*, above the hub, and the other, *H*, below, provided, respectively, with lugs *b d*, with which the arms *D E* will engage in the usual manner for knob-latches.

On the latch *F* is a pivot, *e*, upon which is 45 hung the lever, one arm, *f*, extending upward, the other, *h*, downward. To the upper arm, *f*, one end of a spring, *I*, is attached, the other 50 end of the spring attached to a fixed point, *i*, in the case, the tendency of the spring being to

draw that arm *f* forward—that is, toward the face-plate.

L is the latch-bolt, of the usual bevel-nose shape, extending through a mortise in the 55 face-plate in the usual manner. Its tail *M* is constructed with a head, *m*, at its inner end. The arm *h* of the lever is constructed with a seat in which the tail of the bolt will rest, as seen in Fig. 1, the head *m* standing against 60 the rear side of the arm *h*. A shoulder, *n*, on the inner side of the head or spindle, abuts against the forward end of the slide and so as to take a bearing thereon and serve as a stop against the action of the spring *I*, the tendency of which would be to turn the lever *f h* upon its pivot and draw the bolt inward if it were not for such stop. To reverse the latch, the bolt is drawn outward, as indicated in 65 broken lines, the lever *f h* freely turning upon its pivot in so doing, and when the square portion of the face of the bolt is outside of the case, as indicated in broken lines, Fig. 1, then the bolt may be turned upon its axis and set to either the right or left hand, as occasion may require. In my previous patent a 70 projection or extension was made from the lock-bolt, which, when the latch-bolt was in the drawn condition, would stand forward of the lower end of the arm *h* of the lever; hence 75 would prevent the possibility of drawing the latch-bolt out when the lock-bolt was so drawn into the case, but when the lock-bolt was thrown out then the lever *f h* would be free, and the bolt could be reversed.

To avoid this dependence upon the lock-bolt to hold the latch or prevent its accidental reversal, as well as to adapt the invention to knob-latches in which no lock-bolt is provided, is the object of my present invention; and it 80 consists in constructing the lever *f h* with an arm extending rearward into a slot transversely across the hub, and so that in turning the said lever, as in the act of reversing the bolt, the said arm will be drawn down into the opening 85 through the hub, and so that when the knob-spindle is introduced through the knob it will prevent such turning of the said arm into the hub, and thereby prevent reversing of the latch-bolt except when the knob-spindle is 90 out of the hub.

In carrying out my invention I construct

the lever f h with an arm, P , extending rearward and preferably from a point above the pivot e . This arm extends over the hub, and the hub is constructed with a transverse slot, 5 r , in the plane of the lever P , and so that the lever P may work through that slot and into the opening through the hub, as indicated in broken lines, Fig. 1; hence when the knob-spindle is removed the bolt may be reversed 10 by withdrawing its nose, as before described, thereby turning the lever f h , and in such turning of the lever f h the free end of the arm P passes down into the opening in the hub, as seen in broken lines, Fig. 1; but when the knob-spindle is introduced, then such entrance of 15 the arm P into the opening is prevented, and consequently the latch-bolt cannot be reversed when the knob-spindle is in place. By this construction the reversing mechanism is made 20 entirely independent of the locking mechanism, and which locking mechanism may, if desired, be entirely dispensed with.

In knob-latches which are constructed to be placed upon the surface of the door, in contradistinction to a mortise-latch and such as are 25 commonly called "rim-latches," it is often desirable to provide a device which will lock the latch-bolt in its thrown condition, so that when the door is closed it may be substantially 30 locked without the necessity of a lock-bolt and key.

Various levers, stops, and catches have been arranged to engage the hub or slide when in their thrown or normal condition and so as 35 to prevent the turning of the knob to draw the bolt. These have usually been made either by a pivoted lever, by a vertical slide in the rear edge of the case, or a longitudinal slide in the top of the case; but in either case it is 40 difficult to detect whether or not the bolt is locked without attempting to turn the knob or a careful inspection.

The object of this part of my invention is to provide a stop for the latch-bolt which 45 will not only readily indicate the locked or unlocked condition, but will make the lock sure, and will not be liable to derangement; and it consists in a slide arranged in rear of the hub and movable in a diagonal plane to- 50 ward and from its locking position, and as more fully hereinafter described.

R is the slide, arranged diagonally through an opening in the rear edge of the case, and supported on a suitable bearing. On its under surface is a rib, s , parallel with a corresponding rib, t , in the case. On the reverse side of the slide R a spring, u , is arranged to bear between the slide and the plate of the case, as seen in Fig. 2. The outer end of the 55 slide R is fitted with a convenient thumb-piece, T , by which the bolt may be moved outward,

as indicated in broken lines, Fig. 1, or return. The inner end or nose, w , of the slide, when the slide is inward, stands in the path of the slide H or arms of the hub, as the case may be, and 65 so that the knob cannot be turned when the slide is in that condition; but the slide withdrawn, as indicated in broken lines, Fig. 1, it is out of the path of the slide or hub, and so that the mechanism is free to be worked by 70 the knobs. As the slide R is drawn outward the rib s on the slide rides over the rib t on the case, as indicated in broken lines, Fig. 2. The rib s , falling down outside the rib t , forms a substantial stop to prevent the accidental return of the slide, and the same rib, when the slide is thrown inward, prevents the return of 75 the slide under the pressure that may be brought to bear upon it in turning the knob.

This construction is very simple, adds but a trifling cost to the manufacture of the lock, its 80 operation is readily understood, and it indicates by its position whether or not the latch is locked.

From the foregoing it will be understood 85 that I do not claim, broadly, a slide arranged in the case with a projection extending therefrom by means of which the said slide may be thrown into a position to lock the latch so that it cannot be operated by the knobs. 90

I claim—

1. In a latch, the combination of the slide F , mechanism, substantially such as described, to impart forward and back movement to said slide, a latch-bolt, a lever, one arm, h , of which 95 extends into connection with the bolt forward of a shoulder thereon, and a spring in connection with said lever, and arranged to force the said arm h rearward against said shoulder on the bolt, the said lever constructed with an 100 arm, P , extending rearward toward the hub, and the hub constructed with a transverse slot, r , in the plane of the said arm P , substantially as described.

2. In a knob-latch, the combination of the 105 hub C , and the latch-bolt operated by the rotation of said hub, with the slide R , arranged in diagonal guides in rear of said hub, substantially as and for the purpose described.

3. In a knob-latch, the combination of the 110 hub C , and the latch-bolt operated by the rotation of said hub, with the slide R , arranged in diagonal guides in rear of said hub, the said slide R constructed with a rib, s , upon one 115 surface, and the case with a corresponding rib, t , with a spring, u , upon the reverse side of the slide, substantially as described.
